UNITED STATES PATENT OFFICE.

WILLIAM S. ELLIOTT, OF PITTSBURGH, PENNSYLVANIA.

TREATMENT OF LIQUIDS.

Original No. 1,321,999, dated November 18, 1919, Serial No. 18,268, filed March 31, 1915. Application for reissue filed April 22, 1924. Serial No. 708,322.

To all whom it may concern:

Be it known that I, WILLIAM S. ELLIOTT, a citizen of the United States, residing at Pittsburgh, Allegheny County, Pennsylvania, have invented a new and useful Improvement in the Treatment of Liquids, of which the following is a full, clear, and exact description, reference being had to the accompanying drawings, forming part of this specification.

My invention has relation to the treatment of liquids for the purpose of removing the air and other gases contained or dissolved therein. While applicable to the treatment of other liquids, it is of particular advantage in the treatment of water for industrial purposes. It is a well known fact that the air contained in steam and water causes boiler corrosion, and also corrosion of the valves, pipes, fittings, and other metal parts with which the water or steam comes in contact. Besides the air, water contains other gases dissolved therein, such as carbon dioxide.

The object of the present invention is to provide a simple method and means for the treatment of water or other liquids by which a maximum percentage of the air and other gases contained therein may be removed from the liquid before the latter is used.

The present invention involves broadly the treatment of liquid to effect the release therefrom of its contained air and other gases and by subjecting the same to such conditions that there is produced a change of phase of such a percentage of all of the liquid being treated as to ensure the removal of substantially all of the air.

In the illustrated method of producing this change of phase or evaporation of a definite percentage of the liquid, the liquid is admitted into a receiver, into a region of vacuo, at such a temperature that it can exist only as superheated vapor; and is there caused to boil at a temperature lower than that corresponding to the temperature of the liquid immediately before it enters the receiver. The temperature in the receiver is lowered by lowering the pressure therein by any suitable means, such as a vacuum pump connected thereto. A condenser is preferably interposed between the vacuum

pump and the receiver for condensing such hot vapors as are condensable before they reach the pump. The heat given up in this condenser may be used for the preliminary or partial heating of the liquid to be treated.

The nature of my invention will be better understood by reference to the accompanying drawings, in which I have illustrated one method and form of apparatus for carrying out the invention, and which will now be described, it being premised, however, that the particular apparatus shown is illustrative only and that the invention is capable of various other embodiments within the scope of the appended claims.

In the accompanying drawings—

Figure 1 is a view partly in side elevation and partly in section, and largely diagrammatic, of one form of apparatus for carrying out the invention;

Figure 2 is a diagram of a portion of the apparatus showing a modification, and

Figure 3 is a diagram showing one arrangement of apparatus for using the treated liquid.

In these drawings, the numeral 2 designates a suitable heating tank or receptacle into which the liquid to be treated is conducted by means of the supply pipe 3. This pipe is shown as entering the upper portion of the heater at the central portion thereof, and is branched as indicated at 4, these branches supplying the spray pans 5. These pans are shown as having overflow or spray troughs 6 which discharge onto a suitable arrangement of distributors 7. Pipe 3 is provided with a control valve 8 having actuating connections 9 with a float 10 with

in the heater whereby a substantially constant level of the water is maintained. 11 designates an overflow chamber within the heater and 12 a discharge pipe therefor. This chamber 11 not only takes care of any overflow which may occur in case the level should for any reason rise beyond its normal, but it also takes care of the entrainment from the steam supply pipe 13. The latter opens into an offset portion 14 of the heater 2 and is arranged to discharge against a separator plate 15, the drip from which falls into the chamber 11. The purpose of the separator 15 is to separate out

any oil which may be entrained with the steam in pipe 13. The steam delivered by this pipe is employed for the purpose of heating the water in the tank, although any other heating means may be employed.

16 designates a receiver which is connected by a pipe 17 with the discharge of the heater 2. The pipe enters the upper portion of the receiver and the latter is provided with spray pans 18 and distributors 19 similar to those in the heater. Any other suitable means may, however, be provided for receiving the water as it enters the receiver. 20 is a control valve for the pipe 17, and 21 is a control float therefor. 22 is the actuating connection between the float and the valve. 23 is an offtake pipe for the treated water leading to a pump 24.

The receiver 16 is connected with a vacuum pump 25 through a condenser 26 by means of the pipes 27 and 28. The condenser 26 has a water supply connection at 27^a discharging into the bottom chamber 30, a bank of heating tubes 29 connecting this chamber 30 with an upper chamber 30^a. The pipe 3 is connected to the outlet of this chamber 30^a. 31 is a sediment discharge or clean-out connection for the receiver.

The operation is as follows: Water entering the condenser 26 from the pipe 27^a passes upwardly through the tubes 29 to the chamber 30^a, and thence into the heater 2 by way of the pipe 3. It is brought to the desired temperature in this heater and is then discharged into the receiver in which a partial vacuum is maintained by the action of the pump 25. The effect of this vacuum upon the water entering the receiver is to cause it to boil at a temperature which is lower than the temperature of the liquid immediately before it enters the receiver. By maintaining a sufficient degree of vacuum in this receiver, the water entering it is immediately subjected to a violent boiling action and is in part rapidly converted into vapor. In fact, the boiling action which occurs is of such a violent character that it is in the nature of an explosion or flashing. The water then flows down over the series of distributors in a distributed or film-like condition, so that all portions thereof are subjected to the vacuum action. The combined effect of the flashing or explosion and of the vacuum acting upon the water in moving over the distributors results in the air and other dissolved gases contained in the water being extracted to a maximum extent. The water vapor and other gases thus liberated by the boiling are drawn off through the condenser 26 by the action of the pump 25; and in passing over the bank of tubes 26 impart a very considerable degree of heat to the water contained in said tubes before it enters the heater 2. At the same time, by reason of

the cooling action of the water in the pipes 26 a large percentage of the condensable vapors are condensed, and the liquid of condensation is drawn off by the action of a suitable pump 32 through the pipe 33, or otherwise disposed of. For instance, instead of the pump 32, I may (as shown in Figure 2) elevate the condenser, as indicated at 26^a, to a height above the heater 2^a such as to create a head of water in the U-shaped tube 34 leading into the heater 2^a sufficient to discharge the water from the condenser into the heater, against the action of the vacuum in the condenser.

In Figure 3, I have shown diagrammatically an arrangement of boiler, turbine and condenser apparatus for utilizing the treated water. In this apparatus the pump 24, before referred to, delivers the purified water through the pipe 35 into a boiler 36. The steam generated in this boiler is conducted by the pipe 37 to the turbine 38. The exhaust of this turbine is connected by the pipe 39 with a condenser 40 which may be of any well known type. This results in a very considerable percentage of the contained scale-forming elements in the water being precipitated to the bottom of the receiver in the form of mud which can be readily removed. This is also a valuable feature of my invention.

On account of the removal of the air from the water in the manner described, the steam reaches the condenser 40 in a condition practically free from air, provided there is no leakage in the pipe line between the condenser and turbine.

With the old condensers employing a large dry pump, all of the air and other gases must be extracted by the use of very large vacuum air pumps, working against a high vacuum. By the employment of my system, the dry pump at the main condenser need be only of a small per cent of the capacity of that heretofore required, as a large percentage of the air has already been removed from the liquid at a vacuum pressure which is but a small percentage of that employed in the main condenser. This results in great economy in the operation of the system. In actual operation I have found that under economical commercial operating conditions my invention will effect a separation of ninety to ninety-eight per cent of the contained air. It will accomplish a separation such that the remaining dissolved gases will, at a temperature of thirty-two degrees Fahrenheit at 14.7 pounds per square inch, occupy a volume of .2 per cent to .1 per cent, as computed upon the volume of the dissolving liquids. These figures apply to substantially all simple gases which are found dissolved in natural air as a mixture or constituent of a mixture, with the exception of carbon dioxid. The

latter is separated to as complete an extent as boiling it for a limited time is able to accomplish.

My invention also reduces all soluble carbonates dissolved in the liquid in the form of bi-carbonates from the state of solubility to that of insolubility.

Another advantage of the present invention arises from the provision of a method whereby there is produced such an evaporation or change of phase of the liquid as to result in the release of substantially all of the contained air, and the subsequent conveying of this substantially air-free liquid to a point of utilization thereof.

A further advantage of my invention is, that in its employment the slight heat losses which occur are more than recovered by the gain in the relative power required to operate the large vacuum pumps heretofore required in the operation of condensers, to say nothing of the gain due to the increased vacuum in the condensers. It will be readily understood that the form of the various apparatus described can be widely varied, and that any suitable form of heater and receiver can be used. Where the water to be treated is already at the proper temperature the heater 2 may be entirely omitted and the water conducted directly to the receiver, and various other changes can be made.

What I claim is:

1. The herein described method of treating liquids for the removal of air and other contained gases, which consists in heating the liquid to be treated and then introducing the same into a chamber, maintaining a pressure in said chamber lower than the pressure corresponding to the temperature of the liquid immediately before entering said chamber, distributing the liquid in said chamber, whereby it is subjected to a boiling action to a degree corresponding to the pressure in the receiver, utilizing the vacuum producing means to draw the vapors and gases produced by the boiling through a condenser, conveying substantially air-free liquid from the chamber to a point of utilization thereof, and controlling the introduction of liquid into said chamber substantially wholly in accordance with the demands on said chamber for such air-free liquid, substantially as described.

2. The herein described method of treating liquids for the removal of air and other contained gases, which consists in heating the liquid to be treated and then introducing the same into a chamber substantially wholly in accordance with the demands on said chamber for the treated liquid, maintaining a pressure in said chamber lower than the pressure corresponding to the temperature of the liquid immediately before entering said chamber, distributing the liquid in said receiver, whereby it is subjected

to a boiling action to a degree corresponding to the pressure in the chamber, exhausting the vapors and gases from the receiver and passing them through a condenser, and passing the liquid to be heated through said condenser, substantially as described.

3. The method of treating liquids for the removal of air and other gases contained therein, which consists in introducing the liquid into a chamber, distributing the liquid in said chamber, continuously maintaining in said chamber pressure and temperature conditions such as to change the phase of said liquid to a percentage sufficient to release substantially all of the air contained therein, and conveying the substantially air-free liquid from said chamber to a point of utilization thereof, substantially as described.

4. The method of treating liquids for the removal of air and other contained gases, which consists of introducing the liquid into a suitable apparatus, maintaining in said apparatus continuous pressure and temperature conditions to change the phase of said liquid to a percentage sufficient to release substantially all of the air contained therein, and conveying the substantially air-free liquid from said apparatus to a point of utilization thereof, substantially as described.

5. The method of treating liquids for the removal of air and other contained gases, which consists in introducing the liquid into a chamber, continuously maintaining in said chamber pressure and temperature conditions to change the phase of said liquid to a percentage sufficient to release substantially all of the air contained therein, causing the liquid to flow downwardly in a distributed condition through said chamber, and conveying the substantially air-free liquid from the chamber to a point of utilization thereof, substantially as described.

6. The method of treating liquids for the removal of air and other contained gases, which consists in introducing the liquid in a heated condition into a chamber, continuously maintaining a sufficient vacuum in said chamber to cause a violent ebullition or flashing of the liquid on entering said chamber under the action of the heat contained in said liquid, and causing the liquid to flow through said chamber in a distributed or film-like condition subject to the action of the vacuum therein, substantially as described.

7. The method of treating liquids for the removal of air and other gases and also for the removal of scale-forming elements contained therein, which consists in introducing the liquid into a chamber in heated condition, continuously maintaining a sufficient vacuum in said chamber to cause a violent ebullition or flashing of the liquid as it en-

ters said chamber under the action of the heat contained in the liquid, whereby the air and contained gases are liberated and scale-forming elements precipitated, and conveying substantially air-free liquid from said chamber to a point of utilization thereof, substantially as described.

8. The method of treating liquids for the removal of air and other contained gases, which consists in introducing the liquid into a chamber in a heated condition, maintaining a sufficient vacuum in said chamber to cause a violent ebullition or flashing of the liquid as it enters said chamber under the action of the heat contained therein, causing the liquid to flow through said chamber in a distributed condition while subjected to the action of the vacuum therein, automatically controlling the level of the liquid in said chamber, and conveying substantially air-free liquid from said chamber to a point of utilization thereof, substantially as described.

9. The method of treating liquids for the removal of air and other contained gases, which consists in introducing the liquid into a chamber at a relatively high temperature, continuously maintaining in said chamber a pressure sufficiently lower than the vapor pressure of the hot liquid before it enters said chamber to cause a violent ebullition or flashing of the liquid as it enters the chamber, removing the liberated air and gases from said chamber, utilizing the same as a heating medium, and conveying substantially air-free liquid from said chamber to a point of utilization thereof, substantially as described.

10. The method of treating liquids by the removal of air and other contained gases, which consists in introducing the liquid in a heated condition into a chamber, continuously maintaining in said chamber a pressure sufficiently lower than the vapor pressure of the liquid at its temperature before entering the chamber to cause a violent ebullition or flashing of the liquid as it enters the chamber, and withdrawing the heated vapor and gases from the chamber and utilizing the same for heating the liquid before it is introduced into the chamber, substantially as described.

11. The method of deaerating liquid, comprising providing a receiver having a liquid space and a vapor space conveying substantially air-free liquid from said liquid space to a point of utilization of such liquid, automatically supplying to said receiver substantially wholly in accordance with the flow of such air-free liquid from the liquid space, liquid which is at a temperature higher than the temperature in the receiver and which has a substantially constant difference in temperature thereover, and maintaining said substantially constant differ-

ence in temperature, substantially as described.

12. The method of deaerating liquid, comprising providing a receiver having a liquid space and a vapor space conveying substantially air-free liquid from said liquid space to a point of utilization of such liquid, automatically supplying to said receiver substantially wholly in accordance with the flow of such air-free liquid from the liquid space, liquid which is at a temperature higher than the temperature in the receiver and which has a substantially constant difference in temperature thereover, and recovering the heat released in the receiver, substantially as described.

13. The method of deaerating liquid, comprising passing the liquid to be deaerated successively through a condenser, a heater and into a receiver, maintaining conditions within said receiver to cause a change of phase of the liquid to a percentage sufficient to release substantially all of the air contained therein, withdrawing substantially air-free liquid from the receiver and conveying the same to a point of utilization of such liquid, and controlling the rate of feed of liquid to the receiver substantially wholly in accordance with the demands for air-free liquid thereon, substantially as described.

14. The method of treating liquids to effect the removal of air therefrom, comprising providing a receiver having an air outlet, feeding liquid to said receiver in a substantially continuous manner, supplying heat to the liquid to an amount to change the phase thereof to a percentage sufficient to release substantially all of the air contained therein, recovering at least a portion of the heat released in the receiver, and withdrawing from said receiver in a substantially continuous manner air-free liquid and conveying it as such to a point of utilization, substantially as described.

15. The method of deaerating liquid, comprising providing a receiver having a liquid space and a steam space, conveying substantially air-free liquid from the liquid space thereof to a point of utilization of such liquid in a practically continuous manner, automatically supplying to said receiver substantially wholly in accordance with the demands for air-free liquid on said liquid space, liquid and heat, feeding the entering liquid through the atmosphere in the steam space of the receiver, and continuously withdrawing air and vapor from the liquid space of said receiver to maintain temperature and pressure conditions in the receiver to cause the liquid to release substantially all of its contained air, substantially as described.

16. The method of deaerating liquid, comprising providing a receiver having a liquid

space and a steam space, conveying substantially air-free liquid from the liquid space thereof to a point of utilization of such liquid in a practically continuous manner, automatically supplying to said receiver substantially wholly in accordance with the demands for air-free liquid on said liquid space, liquid and heat, feeding the entering liquid through the atmosphere in the steam space of the receiver, and utilizing the heat of the air and vapor for pre-heating the liquid supplied to the receiver, substantially as described.

17. The method of treating liquids for the removal of air and other contained

gases, which consists in introducing the liquid into a suitable apparatus, maintaining in said apparatus continuous pressure and temperature conditions to change the phase of said liquid to a percentage sufficient to release substantially all of the air contained therein, conveying the substantially air-free liquid from said apparatus to a point of utilization thereof, and condensing the condensable vapors released by the change of phase and utilizing the condensate, substantially as described.

In testimony whereof, I have hereunto set my hand.

WILLIAM S. ELLIOTT.
